UNITED STATES PATENT OFFICE.

CARL W. SWENSON, OF PROVIDENCE, RHODE ISLAND, ASSIGNOR TO ARNOLD C. MESSLER, OF PAWTUCKET, RHODE ISLAND.

BALL-AND-SOCKET FASTENER.

1,197,967.

Specification of Letters Patent. Patented Sept. 12, 1916.

Application filed April 26, 1916. Serial No. 93,781.

To all whom it may concern:

Be it known that I, CARL W. SWENSON, a citizen of the United States, residing at Providence, in the county of Providence and 5 State of Rhode Island, have invented certain new and useful Improvements in Ball-and-Socket Fasteners, of which the following is a specification.

My invention relates to fasteners of the 10 ball and socket type and has for its essential objects the prevention of accidental disengagement of the members by transverse or other strains; to facilitate the induction and removal of the ball relatively to the socket 15 member; to afford a maximum of resiliency and strength to the socket member; and to attain these ends in a structure and by a process of manufacture which is simple and inexpensive.

20 To the above ends essentially my invention consists in such parts and combinations of parts, and in such steps and combinations of steps as fall within the scope of the appended claims.

25 In the accompanying drawings which form a part of this specification, Figures 1 and 2 are plan and side elevations respectively of the original blank or planchet employed to ultimately form the socket member, Figs. 30 3 and 4, similar views of the same after the first bending operation, Figs. 5 and 6, like views of the same after the piercing operation, Figs. 7 and 8, similar views after the depression of the points, Figs. 9 and 10, like 35 views after the points have been rolled in, Fig. 11, a side elevation of the ball member, Fig. 12, a plan view on reduced scale, of the socket member attached to a fabric, Fig. 13, an enlarged section of the socket on line 40 13-13 of Fig. 7 showing in side elevation the ball member during its entrance into the socket, and Fig. 14, a like section and elevation of the same showing the ball member completely seated in the socket.

45 Like reference characters indicate like parts throughout the views.

In constructing my novel fastener by my novel process a circular flat blank or planchet A as shown in Figs. 1 and 2, is cut from 50 a strip of thin metal. By a suitable die the center of this is depressed forming when reversed a rim B and dome shaped elevation C, as shown in Figs. 3 and 4. The described blank is next inserted between bending and

piercing dies whereby an annular bend or 55 depression b is imparted to the inner portion of the flange B, and radially disposed cuts c are made in the dome portion extending from the center thereof into the depression b. At the latter points the cuts are enlarged sufficiently to form eyes d. These cuts or piercings, as shown in Figs. 5 and 6, divide the portion C into segments comprising vertical body portions, and converging pointed portions E substantially horizontal in disposition. By suitable dies the portions E are bent in a substantially vertical position, as shown in Figs. 7 and 8, wherein the portions C have a transversely rounded bend, as at f. The points E are next rolled by suitable dies 70 into the form shown in Figs. 9, 10, 13 and 14 so that their extremities g are upwardly directed and spaced somewhat from the curved portion c' of the wall C, which portion originally formed the part of C which carried 75 the points E.

The ball member H comprises the plate i, the ball or head j, and the neck k, all of any preferred usual construction. The ball is adapted to be attached by its base i to a 80 fabric in any manner. The socket member A may also be attached in the usual manner. In the present instance it is shown attached to a fabric L by thread l passing through the 85 openings d.

The complete socket member, therefore, comprises a base plate or flange B having an annular depression b from which extend the outwardly directed walls c' of the resili- 90 ent members C, having rounded crests or shoulders f which merge in curved inwardly directed walls E, whose pointed extremities g are outwardly bent from points g' near their ends. These extremities are normally spaced from the walls c', and the distance 95 between the transversely curved walls E, which form the circular entrance opening of the socket, is less than the diameter of the head j of the ball member, and amply as great as the diameter of the neck k of the 100 ball. Hence when the members are being interengaged the ball head, as shown in Fig. 13, compresses the wall E until such compression is limited by the contact of the point extremities g against the walls c', and 105 even then increased resiliency is afforded by an inward movement of the extremities by compression against said walls. Meanwhile

a further yielding or resilient property is afforded by an outward movement of the wall c' which is facilitated by the bend b at the bases of the segments or tongues C .

5 After the head j in its insertion, passes by the members C , the constituent parts thereof expand and assume a position such as shown in Fig. 14, thus firmly locking the head, but not excessively, since the rounded 10 lower portions of the walls E facilitate disengagement. Insertion is assisted by the rounded upper portions of the walls E .

By the described construction a maximum 15 of resiliency is afforded the socket so as to efficiently engage ball members of different sizes, and yet insure easy insertion and removal.

It will be observed that the points g are slightly spaced from the wall portions c' . 20 It will be understood also that an operative structure of great advantage is attained when the points g are originally in contact with the walls c' .

I claim:

25 1. In a fastener of the type set forth, the combination of a base and annularly arranged segments mounted on the base comprising inwardly directed scroll shaped bearing members adapted to yieldingly engage a ball member and having free terminals engageable with the adjacent curved walls of the said bearing members.

30 2. In a fastener of the type set forth, the combination of a base, and annularly arranged segments yieldingly mounted on the base comprising yielding bearing members adapted to engage a ball member, and extended terminals upon the ends of the bearing members normally out of contact with

the adjacent curved walls of said members 40 and engageable therewith when compressed.

3. In a fastener of the type set forth, the combination of a base, and annularly arranged segments mounted on the base comprising downwardly directed convex bearing members adapted to engage a ball member, and outwardly inclined terminals upon the ends of the bearing members normally out of contact with the adjacent curved walls of said members and engageable 50 therewith when compressed.

4. In a fastener of the type set forth, the combination of a base, and annularly arranged segments on the base comprising outwardly directed walls, curved inwardly 55 directed bearing members, and outwardly directed terminals upon the bearing members located between said members and said walls normally out of contact with the adjacent curved walls of said members and 60 engageable therewith when compressed.

5. In a fastener of the type set forth, the combination of a base, annularly arranged segments on the base comprising outwardly directed walls provided with transverse 65 bends in their bottom portions, curved inwardly directed bearing members integral with the upper portions of the walls and provided with inwardly directed bends in their lower portions, and points integral 70 with the ends of said members terminating adjacent the walls normally out of contact with but compressible against the adjacent curved portions of said members to increase the tension of the latter.

75 In testimony whereof I have affixed my signature.

CARL W. SWENSON.
